UNITED STATES PATENT OFFICE.

MORRIS W. POOL, OF NEW YORK, N. Y., ASSIGNOR, BY MESNE ASSIGNMENTS, TO UNION TYPEWRITER COMPANY, OF JERSEY CITY, NEW JERSEY, A CORPORATION OF NEW JERSEY.

TYPE-WRITING MACHINE.

1,040,406.

Specification of Letters Patent.

Patented Oct. 8, 1912.

Application filed February 20, 1911. Serial No. 609,612.

To all whom it may concern:

Be it known that I, MORRIS W. Pool, a citizen of the United States, and resident of the borough of Brooklyn, city of New York, 5 in the county of Kings and State of New York, have invented certain new and useful Improvements in Type-Writing Machines, of which the following is a specification.

My invention relates to ribbon mechanisms for typewriting machines and one of its objects is to provide a key controlled throw-varying device, for varying the widthwise portion of the ribbon presented to the types by the ribbon throwing or vibrating mechanism, in combination with a stop-varying mechanism controlled by a key separate and distinct from the key for varying the throw.

Another object of the invention is to so combine the key controlled stop-and-throw-varying mechanisms that the throw-varying mechanism cannot be re-set by its key prior to the operation of the stop-varying mechanism, which must be re-set as a prerequisite to the re-setting of the throw-varying mechanism; or in other words, to provide that one of the mechanisms acts as a check on the other.

Another object is to improve the ribbon vibrator.

Other objects will hereinafter appear.

To the above ends my invention consists in the features of construction, combinations of devices and arrangements of parts hereinafter described and particularly pointed out in the claims.

While my invention may be adapted to various styles of writing machines, the preferred embodiment of the invention is shown 40 herein in connection with a No. 10 Remington visible typewriting machine, Figure 1 being a side elevation of said machine embodying my invention, parts being omitted and parts broken away; Fig. 2, a fragmentary perspective view, taken from the rear, of the ribbon mechanism; Fig. 3, a rear view of part of the ribbon mechanism taken in vertical section; Fig. 4, a vertical sectional view taken on a plane represented by the line x-x 45 in Fig. 3 and looking toward the right; and Figs. 5 and 6, perspective views of a modified construction of ribbon vibrator.

As appears from Fig. 1, the main frame of the machine comprises a base 1, corner posts 2 and a top plate 3, and supports printing instrumentalities comprising type

bars 4 pivoted on hangers 5 secured to a vertical stationary segmental support 6, each type bar being connected through a link 7, lever 8 and link 9 with a key lever 10 having a fulcrum 11 and a restoring spring 12. The type bars are segmentally arranged and co-operate with the front face of a rotary platen 13 supported on a vertical shifting platen frame 14 connected by links 15 to a carriage truck 16 which co-operates through anti-friction rolls 17 with fixed trackways 18 above the top plate 3. The platen carrier or carriage comprising the truck and platen frame is impelled leftward by a carriage power or spring drum 19 with which it is connected by a band 20. Leftward step-by-step movements of the carriage are controlled by escapement devices (not shown) which are connected by a link 21 with a crank arm 22 on a rock shaft 23 provided near its ends with crank arms 24 from which are suspended by links or arms 25 a universal bar 26 underlying the set of key levers 10 and being operative thereby. The platen and platen frame are adapted to be shifted on the truck through a shift rod 27 which provides a track for a roller 28 mounted on the platen frame. The shift rod is connected at its ends by vertical arms 29 with a shift frame bar 30 having at its ends depending arms 31 pivoted to shift key levers (not shown), said levers operating to shift the frame comprising the bar 30, rail 27 and uprights 29 upward and downward to shift the platen and platen frame correspondingly.

Vertically disposed ribbon spools of which the left-hand one is shown and designated as 32, are arranged below and forward of the platen, each ribbon spool being mounted on a shaft 33 which carries a beveled gear 34, said gear being connected with the spring drum by a train of mechanism comprising intermeshing beveled gear wheels 37 and 38. The driving shaft 36 is shiftable endwise to bring one or another of the pinions 35 into mesh with its co-operating beveled gear 34, thus alternately connecting the ribbon spools with the driving shaft and reversing the direction of longitudinal feed of the ribbon.

The ribbon designated by the numeral 39 is wound on the spools 32 and guided upward, inward and rearward toward the printing point. While a single-color ribbon 110 may be employed, my invention is especially applicable to ribbons having printing

fields of different characteristics, and accordingly the ribbon 39 is such a ribbon, it being divided longitudinally into printing fields *a* and *b* of different characteristics, as colors. Opposite the printing point the ribbon is threaded through a vibratory carrier or vibrator 40 guided on a member 41 secured at the rear of a segmental cover plate 42 which is fixed to the type bar segment 6.

10 The devices for vibrating the ribbon vibrator and ribbon at printing operation comprise an operating lever which includes two parts or members 43 and 44, the member 43 being pivotally connected to the vibrator at 45 and 15 being itself pivoted at 46 to the lever part 44, which is fulcrumed at 47 on a fulcrum bracket 48 on the frame plate 42. The lever parts 43 and 44 are maintained in normal relationship by devices comprising a lever 20 49 fulcrumed at 47 co-axially with the lever part 44. The lever 49 is connected through a link 50 with the tail 43^a of the lever 43 and the opposite arm of said lever 49 is pivotally connected at 51 with an arm 25 52 fixed at 53 to the shift bar 30. The normal lower case position of the lever parts is illustrated in Fig. 2. At printing operation the two lever parts are operated as a single member without substantial change 30 of relationship; but when the platen is shifted it operates through the arm 52, lever 49 and link 50 to alter the normal relationship of the lever parts 43 and 44, the part 43 turning on the pivot 46 to lift the vibrator and ribbon to a new normal position corresponding with the shifted position of the platen. From its shifted position the lever part 43 will again be operated as before, together with the lever part 44 at 35 40 printing operation. During the shifting movements of the lever part 43 due to the platen shift the lever part 44 will remain unaffected. These parts 43 and 44, although in themselves levers, have been designated 45 as lever parts since together they are comprised in the operating lever as a whole, which operating lever is fulcrumed at 47, is connected at 45 to the vibrator and is connected at the opposite side of the fulcrum to actuating devices which comprise 50 a stud 54 engaging in a slot 55 in the lever part 44, said stud being fixed to the upper end of an actuating link 56 off-set rearwardly as indicated at 56 to an arm 58 on 55 the rock shaft 23. It will be understood that at printing operation the universal bar 26 is actuated, rocking the shaft 23 and vibrating the link 56, said link in turn actuating the operating lever 43, 44 which vibrates the vibrator 40 and raises and lowers the ribbon first to cover the printing point to receive the type impression and then to lower the ribbon to expose the imprint on the paper.

60 65 The stud 54 is settable at different points

lengthwise of the slot 55 to vary the extent of movement imparted by the link 56 to the operating lever 43, 44 and thus vary the printing field of the ribbon. When the stud is set farthest from the fulcrum 47, as indicated in Fig. 2, the vibrator will be raised to its least extent and so as to present the upper ribbon field *a* to the types. Throw-varying means are provided for resetting the stud 54 nearer the fulcrum 47. Said throw-varying means comprise a slotted shift frame 59 (Figs. 2 and 3) guided in part by a screw 60 on the bracket 48. The shift frame 59 is formed with a downward extension 59^b provided with a slot 61 in which the stud 54 engages. The tail or extension 59^b of the shift frame is off-set rearward and extended laterally, being pivotally connected at 62 with a lever 63 fulcrumed at 64 on a bracket 65 screwed or otherwise secured to the periphery of the type bar segment. The off-set arm of the lever 63 is pivotally connected at 66 with a crank arm 67 secured to the rear end of a rock shaft 68, said rock shaft bearing at its rear end in an extension of the bracket 65 and extending forward to a bracket 69 supported on the left-hand front corner post 2, said shaft bearing on and projecting through said bracket 69 and being provided at its forward end with a knurled finger button 70 by which the shaft may be rocked back and forth. The rotary movements of the shaft operate through the crank arm 67 and lever 63 to slide the shift frame 59 back and forth. When the shift frame is slid inward from the Fig. 2 position it will operate to shift and re-set the stud 54 and link 56 so that they will operate nearer the fulcrum 47 of the operating lever. The result is that at printing operation a greater extent of throw is communicated to the operating lever and the ribbon vibrator is lifted to a greater height presenting the lower ribbon field *b* to the action of the types. The ribbon throw-varying mechanism above described is that with which the machine has heretofore been provided.

In carrying out my invention I provide novel stop devices for the vibrator actuating mechanism, said stop devices being controlled by a key or finger piece separate from and independent of the finger piece or key 70 which controls the throw-varying means. The novel stop devices, as herein shown, comprise a stop member 71 which is pinned at 72 to a rock shaft 73 and is provided with two radial projections which terminate in stop faces 74 and 75, the stop face 74 being at a greater distance from the axis of rotation of the shaft 73 than is the stop face 75. The stop faces are adapted to co-operate with the bottom face of a lug 76 formed at the rear end of the lever part 44. The rock shaft 73 extends leftward, termi-

nating outside the machine in a knurled finger button or key 77 which is suitably secured in place. The rock shaft 73 bears near its inner end in an extension 65^a of the stationary bracket 65, the outer end portion of the rock shaft 73 bearing in a bracket 78 secured to the top plate 3 and provided with an extension 78^a to which is pivoted at 79 a spring arm or detent 80. The detent is 10 pinched to form an engaging-V 80^a and is provided at opposite sides of the engaging part 80^a with stop extensions 80^b and 80^c. The part 80^a is engageable with V-notches 81 and 82 formed in a collar 83 fixed to the 15 rock shaft 73 to the right of the stationary bearing bracket 78.

When the detent 80 is engaged with the notch 81 as shown in Fig. 2, the stop face 74 is uppermost and in the path of the co-20 acting stop 76 on the lever part 44. This relation of the stop faces corresponds with the arrangement of the throw-varying mechanism shown in Fig. 2 wherein the stud 54 is located to give the operating lever the 25 shorter of its two predetermined extents of vibrating movement. The height of the stop face 74 is such that the stop 76 will contact with it to arrest the ribbon throw or 30 vibrating mechanism when said mechanism has raised the ribbon high enough to present the ribbon field *a* to the type. The co-acting stops 74 and 75 will operate to prevent overthrow of the ribbon and will insure that the printing is confined to the ribbon field *a*.

35 Since the throw-varying and stop varying devices are controlled by separate and independent keys or hand devices there is a possibility that the operator, when resetting or readjusting the throw-varying mechanism 40 might forget to correspondingly re-adjust or reset the stop mechanism. To guard against this possibility I provide check devices which prevent the re-adjustment of the throw-varying mechanism until 45 the stop mechanism has been itself reset. The check devices constitute means for insuring that the independent throw varying and stop mechanism shall be set and reset in a predetermined order; that is, the stop 50 mechanism shall be reset first and the throw varying mechanism last. In the present instance the check or preventive devices comprise an arm 84 fixed to and rising from the rock shaft 73 and having a rearwardly bent 55 extension or stop proper 85 which lies in the path of movement of the upper arm of the lever 63 so that the lever cannot be turned on its fulcrum in the course of resetting the throw-varying mechanism until the stop or 60 check 85 has been swung out of the way, the only manner of accomplishing this being by turning the rock shaft 73 to reset the stop mechanism. For instance, in the Fig. 2 position of the parts wherein both the vibrat- 65 ing mechanism and the stop mechanism are

set to provide for the proper movement and arrest in printing position of the ribbon field *a*, the stop 85 is at the left of the lever 63 viewed from the rear of the machine and in said Fig. 2. If now the operator should attempt to reset the stud 54 by turning the finger button 70 in the direction of the arrow in Fig. 2, the stop 85 would lock the parts from movement. Accordingly the operator must first turn the stop key or finger button 77 forward in the direction of the arrow in Fig. 2, until arrested by the contact of the front face of the collar 83 with the stop 80^c, thus swinging the stop 85 out of the path of the lever 63, causing the detent spring to ride out of the notch 81 and into the notch 82, the V 80^a passing slightly beyond the point of said notch and engaging with the lower portion of the rear inclined face thereof. It will be understood that the 85 rock shaft 73 will thus be put under a slight tension which tends to turn it oppositely from the arrow in Fig. 2. Consequently if now the stud 54 be re-adjusted nearer the fulcrum 47 (as shown in Fig. 3) 90 by turning the finger button 70, the lever 63 will be swung across past the rear end of the stop 85, as shown in Fig. 3, and said stop will thereafter turn backward slightly until the spring-V, 80^a, seats itself in the bottom 95 of the notch 82. This slight backward turning movement re-sets the stop 85 in the path of the lever 63 but at the opposite side of said lever, as will be understood from a consideration of Figs. 3 and 4. The engagement of the spring detent with the notch 82 maintains the rock shaft 73 in its new or re-set position in which position the stop face 75 is set in the path of the stop 76 so that it will arrest the operating lever 43, 44 105 when it has been given its greater extent of throw by the re-set actuating stud 54. When the vibrating mechanism is arrested by the engagement of the stop 76 with the stop 75, the ribbon field *b* will be opposite 110 printing point and the stops will prevent said ribbon field from being overthrown past the printing point.

It will be seen that when set in the position shown in Figs. 3 and 4, the stop 85 will 115 prevent the resetting of the vibrating mechanism in the Fig. 2 position since the lever 63 will be locked by the stop 85 against swinging back from the Fig. 3 to the Fig. 2 position. Consequently as a pre-requisite to re-setting the vibrating mechanism for the upper ribbon field *a*, it will be necessary to 120 re-set the stop mechanism by turning the rock shaft forward slightly to permit the lever 63 to swing past it when the finger button 70 is turned, and thereafter to turn the rock shaft 73 rearward until arrested by the contact of the rear face of the collar 83 with the stop 80^b. By these operations the 125 stop mechanism will be re-set in the Fig. 2 130

position and the throw-varying mechanism also reset in said position.

It will be observed that the key or finger button 70 is at the front of the machine and the key or finger button 77 is at the left-hand side of the machine, so that these keys or buttons may be conveniently manipulated concurrently by the operator, one key with one hand and one with the other, although they are separate and independent. Thus it will be seen that the advantages of a simultaneous manipulation of throw-varying or stop devices are retained while the difficulties heretofore encountered in practice of successfully adjusting the parts of interdependent throw-varying and stop devices to give corresponding and accurate results are obviated.

The vibrator heretofore described has the tops of the ribbon receiving slots closed and there is no possibility of the ribbon being thrown out of the vibrator, but there are times when the printing portion of the ribbon is thrown higher than it should be between said slots. In order to provide for more perfect control of the printing portion of the ribbon devices may be employed of the character shown in Figs. 5 and 6. Fig. 6 illustrates a vibrator designated as a whole as 86 and provided with parallel upright portions 87 which terminate at their tops in spring forks 88, said forks providing closures at their tops for vertical slots 89. The slots are adapted to receive a ribbon frame 90 (shown in Fig. 5). Said ribbon frame is preferably formed of a single piece of sheet metal which incloses the ribbon in a narrow frame having an opening 91 through which the types may strike. The frame is provided with forwardly extending angular ears 92 which are adapted to fit in the slots 89 in the vibrator, being snapped into place by forcing them down between the spring forks 89, said forks having beveled upper edges and the lower faces of said forks which form the tops of the slots 89 being also slightly beveled to facilitate the removal of the frame from the vibrator. When in place the frame holds the printing portion of the ribbon accurately in position on the vibrator and so that the ribbon passes behind the upper parts of the uprights 87. Preferably, as a matter of convenience, a sheet metal frame 90 may be provided with each ribbon, being arranged on the outer free end of the ribbon so that when the same is to be employed in the machine, the ribbon frame may be readily snapped into place on the vibrator. The ribbon frame prevents the accidental displacement of the ribbon on the vibrator and also prevents the upward displacement of the printing portion of the ribbon due to the momentum imparted to the vibrator at printing operation.

Various changes may be made without departing from my invention.

What I claim as new and desire to secure by Letters Patent, is:

1. In a typewriting machine, the combination of printing keys, variable ribbon vibrating devices, and key operated ribbon stop devices including a plurality of ribbon stops movable alternately into and out of operative position by a different key operation from that by which the vibrating devices are varied and in predetermined order in respect thereof. 70 75

2. In a typewriting machine, the combination of a ribbon vibrator, vibrator actuating devices settable to give different extents of throw to the vibrator, stop devices for said actuating devices, and means normally operative to prevent resetting of said actuating devices, said means being independent of the operation by which the actuating devices are set to vary the throw of the vibrator. 80 85 90

3. In a typewriting machine, the combination of a ribbon vibrator, vibrator actuating devices settable to give different extents of throw to the vibrator, stop devices for said actuating devices, and means connected to said stop devices and normally operative to prevent resetting of said actuating devices. 95 100

4. In a typewriting machine, the combination of a ribbon vibrator, actuating devices therefor, key controlled means for setting said actuating devices to give different extents of throw to the vibrator, stop devices settable by a separate key, and check means for said key controlled means, said check means being independent of the key of said key controlled means. 105 110

5. In a typewriting machine, the combination of a ribbon vibrator, actuating devices therefor, key controlled means for setting said actuating devices to give different extents of throw to the vibrator, stop devices settable by a separate key, and check means for said key controlled means, said check means being movable into and out of operative position by said separate key. 110 115

6. In a typewriting machine, the combination of a ribbon vibrator, actuating devices therefor, means controlled by a finger key for setting said actuating devices to give different extents of throw to the vibrator, ribbon stop devices comprising a plurality of ribbon stops settable in alternation in operative position to correspond with the variation in the setting of the actuating devices, said stops being set by a key operation separate from the setting operation for the actuating devices, and devices for insuring that the setting operation of the throw varying means and of the ribbon stop devices shall take place in predetermined order. 120 125 130

7. In a typewriting machine, the combi-

nation of a ribbon vibrator, actuating devices therefor, means controlled by a finger key for setting said actuating devices to give different extents of throw to the vibrator, 5 stop devices for said vibrator actuating devices, said stop devices being settable by a separate key to correspond with the variation in the setting of the actuating devices, the two keys aforesaid being concurrently 10 operative but in predetermined order.

8. In a typewriting machine, the combination of a ribbon vibrator, actuating devices therefor, means controlled by a finger key for setting said actuating devices to give 15 different extents of throw to the vibrator, stop devices for said vibrator actuating devices, said stop devices being settable by a separate key to correspond with the variation in the setting of the actuating devices, 20 the stop key being operated as a prerequisite to the operation of the first recited key.

9. In a typewriting machine, the combination of a ribbon vibrator, actuating devices therefor, means controlled by a finger key for setting said actuating devices to give 25 different extents of throw to the vibrator, stop devices for said vibrator actuating devices, said stop devices being settable by a separate key to correspond with the variation 30 in the setting of the actuating devices, the two keys aforesaid being concurrently operative, the stop key being operated as a prerequisite to the actuation of said finger key.

35 10. In a typewriting machine, the combination of a ribbon vibrator, actuating devices therefor, means controlled by a finger key for setting said actuating devices to give different extents of throw to the vibrator, 40 stop devices for said vibrator actuating devices, said stop devices being settable by a separate key to correspond with the variation in the setting of the actuating devices, and devices controlled by said stop key and 45 which normally lock the finger key against actuation.

11. In a typewriting machine, the combination of a ribbon vibrator, actuating devices therefor, key controlled means for setting said actuating devices to give different 50 extents of throw to the vibrator, key controlled stop devices for said actuating devices, and check means for said key controlled means, said check means being normally operative and being automatically rendered inoperative.

55 12. In a typewriting machine, the combination of a ribbon vibrator, actuating devices therefor, key controlled means for setting said actuating devices to give different 60 extents of throw to the vibrator, key controlled stop devices for said actuating devices, and normally operative check means for said key controlled means, said check 65 means being automatically rendered inoper-

ative when said key controlled stop devices are actuated.

13. In a typewriting machine, the combination of a ribbon vibrator, actuating devices therefor, key controlled means for setting said actuating devices to give different 70 extents of throw to the vibrator, stop devices for said actuating means, means controlled by a separate key for setting said stop devices, a normally operative lock for 75 said key controlled means, and connections between said lock and said separate key.

14. In a typewriting machine, the combination of a ribbon vibrator, actuating devices comprising an operating member and 80 a link, means controlled by a finger key for varying the normal relationship between said lever and said link, stop devices cooperative with said actuating devices, means controlled by a separate key for varying 85 said stop devices, and a normally operative check for said actuating devices, said check being connected to said separate key.

15. In a typewriting machine, the combination of a ribbon vibrator, an operating 85 lever therefor, an actuating link for said operating lever controlled by the printing key, key controlled means for setting said actuating link to change the throw of the vibrator, a plurality of stops co-operative with 90 said operating lever to arrest it in different abnormal positions, key controlled devices separate from said means for setting said stops, and means for insuring that said key controlled means and said key controlled devices 95 shall be actuated in a predetermined order.

16. In a typewriting machine, the combination of a ribbon vibrator, an operating 100 lever therefor, an actuating link for said operating lever controlled by the printing key, key controlled means for setting said actuating link to change the throw of the vibrator, a plurality of stops co-operative with 105 said operating lever to arrest it in different abnormal positions, key controlled devices for setting said stops, and a lock controlled 110 by said key controlled devices and normally preventing movement of said key controlled means.

17. In a typewriting machine, the combination of a ribbon vibrator; an operating lever; an actuating link; means for resetting said link relatively to said lever, said means comprising a shift frame, a rock shaft, and 115 devices including a second lever between said shift frame and said rock shaft; a stop member provided with a plurality of stop devices co-operative with said operating lever; key controlled connections for setting 120 said stop member; and an abutment controlled by said connections and normally in the path of said second lever.

18. In a typewriting machine, the combination of a ribbon vibrator; an operating 125

- lever; an actuating link; means for resetting said link relatively to said lever, said means comprising a shift frame, a rock shaft, and devices including a second lever between 5 said shift frame and said rock shaft; a stop member provided with a plurality of stop devices coöperative with said operating lever; key controlled connections for setting said stop member; an abutment controlled 10 by said connections and normally in the path of said second lever; and detent devices for retaining said abutment in different normal relationships with said second lever.
19. In a typewriting machine, the combination of a ribbon vibrator, an operating lever, an actuating link, means for resetting said link relatively to said lever, said means comprising a shift frame and operative devices therefor including a second lever, a 15 stop member provided with a plurality of stop devices coöperative with said operating lever, a key controlled rock shaft connected to said stop member, an abutment controlled by said rock shaft and normally in the path 20 of said second lever, and detent devices for said rock shaft, said detent devices maintaining said abutment in different normal relationships with said second lever.
20. In a typewriting machine, the combination of a ribbon vibrator, actuating devices therefor, means comprising a lever for varying the normal relationship of certain 30 of said actuating devices, key controlled stop devices for limiting the extents of movement of said actuating devices, and an abutment connected with said stop devices and normally in the path of said lever.
21. In a typewriting machine, the combination of a ribbon vibrator, vibrating devices, throw-varying devices, stop devices, 40 and a check connected to said stop devices for said throw-varying devices.
22. In a typewriting machine, the combination of a platen, means for shifting the 45 same, a ribbon vibrator shiftable with said platen, vibrating means, throw-varying means, stop means for the vibrating means, and a lock controlled by said stop means for normally preventing the actuation of said 50 throw-varying means.
23. In a typewriting machine, the combination of a ribbon vibrator, actuating devices therefor, key controlled means having a plurality of normal positions and operative 55 to set said actuating devices to give different extents of throw to the vibrator, stop devices for said actuating devices, and a check for said key controlled means, said check being normally operative in both normal 60 positions of said key controlled means and being movable into and out of operation independently of the key of said key controlled means.
24. In a typewriting machine, the combination of a ribbon vibrator, actuating devices therefor, key controlled means having a plurality of normal positions and operative to set said actuating devices to give different extents of throw to the vibrator, stop devices for said actuating devices, a check 65 for said key controlled means, said check being normally operative in both normal positions of said key controlled means, and connections between said check and said stop devices, said check being movable into and out of operative position independently of the key of said key controlled means. 70
25. In a typewriting machine, the combination of a ribbon vibrator having slots provided with spring closures, and a ribbon 80 frame detachably secured in said slots.
26. In a typewriting machine, the combination of a ribbon vibrator having parallel upright portions provided with spring forks, and a rectangular ribbon frame having ears adapted to coöperate with said spring forks to detachably connect the ribbon frame to the vibrator. 85
27. In a typewriting machine, the combination of a ribbon vibrator, and a ribbon 90 frame detachably mounted thereon, said ribbon frame in itself substantially completely inclosing the printing portion of the ribbon and extending over and along the top edge of said printing portion. 95
28. In a typewriting machine, the combination of a ribbon vibrator, actuating devices therefor, devices controlled by a finger key for setting said actuating devices to vary the throw of the vibrator, variable ribbon stop devices settable by a second finger key and special mechanism which necessitates the operation of one of said finger keys before the other can be operated. 100
29. In a typewriting machine, the combination of a ribbon vibrator, an operating lever therefor, means for varying the throw of said lever, a pair of stops arranged at different elevations and adapted directly to arrest the movements of said lever according to adjustment of said stops, means independent of the throw varying means for adjusting said stops, and devices for insuring that said last named means shall be operated in a predetermined order in respect 110 of the throw varying means. 115

Signed at the borough of Manhattan, city of New York, in the county of New York, and State of New York, this 18th day of February, A. D. 1911.

MORRIS W. POOL.
